(57) **CLAIM**

The ornamental design for a sound mixing console, as shown and described.

DESCRIPTION

FIG. 1 is a perspective view of a sound mixing console showing my new design;

FIG. 2 is a top view of the sound mixing console as shown in FIG. 1;

FIG. 3 is a front elevation view of the sound mixing console as shown in FIG. 1;

FIG. 4 is a sectional side elevation view of the sound mixing console taken along the line 4—4 in FIG. 2 and viewed in the direction of the arrows; and,

FIG. 5 is a sectional side elevation view of the sound mixing console taken along the line 5—5 in FIG. 2 and viewed in the direction of the arrows.

The broken line showing on FIGS. 1—5 is for illustrative purposes only and forms no part of the claimed design.

1 Claim, 5 Drawing Sheets
